Primary Examiner—Cynthia E. Ramirez*(74) Attorney, Agent, or Firm*—Woodard, Emhardt, Moriarty, McNett & Henry LLP(57) **CLAIM**

The ornamental design for a winch tensioner bracket, as shown and described.

DESCRIPTION

FIG. 1 is a perspective view of the winch tensioner bracket of the present invention.

FIG. 2 is a top plan view.

FIG. 3 is a bottom plan view.

FIG. 4 is a front elevation. The rear elevation is identical to the front elevation.

FIG. 5 is a side elevation taken from the right side of FIG. 4. The side elevation taken from the left side of FIG. 4 is identical to FIG. 5; and,

FIG. 6 is a perspective view showing environment of the present invention.

The broken line showing of chain and hardware in FIG. 6 is for illustrative purposes only and forms no part of the claimed design.
